VENTILATOR

Perry S. Martin, Harrisonburg, Va.

Application June 24, 1930, Serial No. 463,402

7 Claims. (Cl. 98—83)

This invention relates to ventilators, and has reference, more particularly, to what are ordinarily known as roof ventilators, or ventilator "heads".

5 In connection with a ventilator of the type referred to, I aim to minimize the effect of back pressure upon free exhausting of the air from the building with which the ventilator is used and at the same time preclude entry of rain, snow or 10 sleet.

Another aim of my invention is to secure the maximum aspirating effect from the wind passing over the top of the ventilator, through exclusion of wind currents deflected upward by the 15 roof of the building such as would interfere with efficient functioning of the ventilator.

A further aim of my invention is to attain the above indicated desideratum in a roof ventilator which is simple in construction, inexpensive, and 20 highly efficient as well as reliable in use under all weather conditions.

Other objects and attendant advantages of this invention will be manifest from the detailed description following taken in connection with the 25 attached drawings, wherein Fig. I shows a plan view of my improved ventilator head with a portion thereof broken out to expose important details at the interior.

Fig. II is an axial sectional view of the 30 ventilator head taken as indicated by the arrows II—II in Fig. I.

Fig. III is a side view of a baffle cap which constitutes a part of the ventilator head; while 35 Figs. IV, V and VI are perspective views showing various details of the baffle cap.

As herein delineated, the ventilator head of my invention comprises a tubular neck portion 10 which is adapted to be inserted into an opening through the roof of a building which is to be ventilated. This tubular neck portion 10 is supported by a comparatively deep cylindric band 11 of larger diameter which, as shown in Fig. II, laps the upper edge of said neck portion by a slight margin with provision thereabout of a 45 wide circumferential outlet space 12. The band 11 is supported by a number of circumferentially arranged brackets 13 having downward and upward extremities 14, 15 at opposite ends of their radial arms 16, said extremities being secured 50 respectively to the neck portion and to the band by screw bolts 17, 18.

Axially disposed within the upper part of the band 11, at a level above the top edge of the neck portion 10, is a baffle cap which is comprehensively designated by the numeral 20. This baffle

cap 20 is of conical configuration and of composite construction for penetrability by the exhaust air released from the ventilator head. As shown, the cap 20 comprises a pair of correspondingly dished center pieces 21, 22 which are 60 relegated to different planes through interposition between them of a co-axial collar 23, see Figs. II and VI, and held assembled with the collar by means of an axial screw bolt 24. Attached respectively to the under and upper faces of the 65 sloping flanges of the center pieces 21, 22 by screw bolts 25, 26, are radial segments 27, 28 which are individually fashioned from sheet metal to channel cross section. Referring to Figs. II and III it will be observed that the segments 27, 28 are 70 alternately arranged and overlap one another with their side flanges opposing. To assist assembling and to predetermine proper radial disposal of the segments 27, 28, the center pieces 21, 22 are respectively provided with lugs 29, 30 between which the inner ends of said segments 75 engage as clearly shown in Figs. IV and V. From Figs. IV and V it will be particularly noted that the inner ends of the side flanges of the radial segments 27, 28 are bent over as at 31, 32 to engage behind the lugs 29, 30 of the inner circles, this provision being for greater security of said segments against displacement. Proper registry as between the radial segments 27, 28 of the cap 20 is insured by radial lugs 33, 34 respectively on 80 the underside of the top center piece 21 and on the upper side of the lower center piece 22 arranged to engage aligned notches 35, 36 in the top and bottom edges of the spacing collar 23. In this way, the baffle cap 20 is provided with 85 elongated protected openings 37 through which a portion of the upward exhaust flow from the building is released from the head, as later on more fully explained. The baffle cap 20 is supported within the band 11 by means of brackets 90 40 which are secured to the inside of said band at circumferential intervals in correspondence with the allocation of the brackets 13, said brackets 40 having inwardly extending radial arms 41 which are pierced at their ends for passage of 100 screws 42 that take into the upper center piece 21 of said baffle.

Referring to Figs. I and II, the baffle cap 20 is surrounded by a supplemental inner band 43 having a vertical depth to reach from the level 105 of the upper edge of the outer band 11 down to the level of the outer ends of the upper series of radial segments 27, with formation of an annular out-flow clearance 44 at the top of the ventilator head in line with the annular bottom out- 110

let space 12 aforementioned. As shown in Figs. I and II, the supplemental band 43 is supported by angle spacers 45 whereof the outer flanges engage behind the vertical legs of the brackets 40 5 that support the cover baffle 20, screws 40a serving as a common means for securing the brackets 40 and spacers 45 to the band 11. At a level beneath the lower edge of the supplemental band 45, the neck portion 10 of the ventilator head 10 is surrounded by a downwardly divergent conical guard 46 whereof the periphery is co-extensive with that of the band 11. This conical guard 46 is supported by drop arms 47 depending from the radial arms 16 of the brackets 13. 15 In operation, the air to be exhausted from the building, upon entering the ventilator head via the tubular neck portion 10, diffuses in all directions in seeking the several channels open for its escape. As shown by the arrows in Fig. II, 20 part of the upward flow, in impinging upon the baffle cap 20, subdivides and finds its way out through the protected radial openings 37 between the interlapping channelled segments 27, 28 of said cap, after the manner indicated by the arrows in Figs. I and III. Another part of the upward flow of air passes direct into the external atmosphere through the annular outlet interval 44 between the outer band 11 and the supplemental inner band 43 at the top of the ventilator head. The remainder of the air flows over 25 the top edge of the neck portion 10 and out through the broad annular outlet space 12 between said neck portion and the bottom edge of the outer band 11. It will thus be seen, that, 30 by virtue of the small amount of resistance imposed in my novel ventilator head, ordinarily the outflowing air is substantially free of restraint and therefore free to respond to natural or draft action. In addition to functioning as 35 above described, the baffle cap 20 operates to check back draft under the influence of downward outside air pressure, and, moreover, to prevent rain, snow and sleet from falling into the top of the neck 10 by diverting it for discharge 40 through the bottom outlet space 12 of the ventilator head. In cooperation with the band 11 and the baffle cap 20, the supplemental band 43 acts as a means to prevent entry of driving rain, 45 sleet and snow into the neck 10 of the ventilator at an angle. The exhausting action of the ventilator is obviously promoted through aspiration induced by movement of the wind crosswise of the annular top outlet clearance 44; and the 50 efficiency of the ventilator is materially increased 55 by action of the downwardly flared guard 46 which prevents currents of air, deflected upward by the roof of the building, from entering the ventilator head at the bottom and checking or nullifying the aspiratory action induced in the 60 manner just explained.

Having thus described my invention, I claim:

1. A ventilator head having a tubular neck portion; a comparatively deep superimposed co-axial band of larger diameter vertically lapping the upper edge of the neck portion by a slight margin with provision thereabout of a circumferential space constituting a bottom exhaust outlet; and a conical rain-deflecting baffle cap axially within the top of the band, said cap including spaced channel-section segments alternately overlapping to define radial-outlets for escape of part of the upward exhaust flow from the head. 65
2. A ventilator head having a tubular neck portion; a comparatively deep superimposed co-axial band of larger diameter vertically lapping the upper edge of a neck portion by a slight margin with provision thereabout of a circumferential space constituting a bottom exhaust outlet; and a rain deflecting baffle cap axially within the top of the band having protected radially-arranged elongated openings to permit escape of upward exhaust flow from the head. 70
3. A ventilator head having a tubular neck portion; a comparatively deep superimposed co-axial band of larger diameter vertically lapping the upper edge of the neck portion by a slight margin with provision thereabout of a circumferential space constituting a bottom exhaust outlet; and a rain deflecting baffle cap axially within the top of the band, said baffle cap consisting of a number of radial segments of channel section defining side flanges, said segments being arranged in spaced planes with the side flanges opposing and one overlapping the other with incident formation of protected elongated openings 75 permitting escape of the upward exhaust flow from the head. 80
4. A ventilator head having a tubular neck portion; a comparatively deep superimposed cylindrical band of larger diameter vertically lapping the upper edge of a neck portion by a slight margin with provision thereabout of a circumferential space constituting a bottom exhaust outlet; and a rain-deflecting baffle cap axially within the top of the band, said baffle cap comprising a pair of center pieces and alternately arranged radial segments of channel cross section defining side flanges, said radial segments being supported in vertically spaced relation by the center pieces with the side flanges interlapping to form protected elongated openings for escape of upward exhaust flow from the head. 90
5. A ventilator head having a tubular neck portion; a comparatively deep superimposed co-axial band of larger diameter vertically lapping the upper edge of the neck portion by a slight margin with provision thereabout of a circumferential space constituting a bottom exhaust outlet, and a conical rain-deflecting baffle cap axially within the top of the band, said cap including vertically spaced channel-section segments alternately overlapping with their side flanges opposing to define radial-outlets permitting escape of part of the upward exhaust flow from the head, said baffle cap having an area greater than that of the neck portion but somewhat less than that of the band with provision of an outlet clearance for upward annular escape of exhaust air at the top of the head. 100
6. A ventilator head having a tubular neck portion; a comparatively deep superimposed co-axial band of larger diameter vertically lapping the upper edge of the neck portion by a slight margin with provision thereabout of a wide circumferential space constituting a bottom exhaust outlet; a rain deflecting baffle cap axially within the upper portion of the band having protected elongated openings defined by upper and lower alternately arranged channel-section radial segments for upward exhaust flow released through the head, said cap having an area somewhat less than that of the band with formation of an annular exhaust clearance at the top of the head; and a supplemental inner band reaching from the level of the upper edge of the outer band to the outer ends of the upper series of radial segments to form, in conjunction with the outer band, an annular exhaust outlet clearance at the top of the head, said supplemental band also serving as a guard to arrest driving rain, sleet or snow entering the an- 110
7. A ventilator head having a tubular neck portion; a comparatively deep superimposed co-axial band of larger diameter vertically lapping the upper edge of the neck portion by a slight margin with provision thereabout of a circumferential space constituting a bottom exhaust outlet; and a rain deflecting baffle cap axially within the top of the band having protected radially-arranged elongated openings to permit escape of upward exhaust flow from the head. 115
8. A ventilator head having a tubular neck portion; a comparatively deep superimposed co-axial band of larger diameter vertically lapping the upper edge of the neck portion by a slight margin with provision thereabout of a circumferential space constituting a bottom exhaust outlet; and a rain deflecting baffle cap axially within the top of the band having protected radially-arranged elongated openings to permit escape of upward exhaust flow from the head. 120
9. A ventilator head having a tubular neck portion; a comparatively deep superimposed co-axial band of larger diameter vertically lapping the upper edge of the neck portion by a slight margin with provision thereabout of a circumferential space constituting a bottom exhaust outlet; and a rain deflecting baffle cap axially within the top of the band having protected radially-arranged elongated openings to permit escape of upward exhaust flow from the head. 125
10. A ventilator head having a tubular neck portion; a comparatively deep superimposed co-axial band of larger diameter vertically lapping the upper edge of the neck portion by a slight margin with provision thereabout of a circumferential space constituting a bottom exhaust outlet; and a rain deflecting baffle cap axially within the top of the band having protected radially-arranged elongated openings to permit escape of upward exhaust flow from the head. 130
11. A ventilator head having a tubular neck portion; a comparatively deep superimposed co-axial band of larger diameter vertically lapping the upper edge of the neck portion by a slight margin with provision thereabout of a circumferential space constituting a bottom exhaust outlet; and a rain deflecting baffle cap axially within the top of the band having protected radially-arranged elongated openings to permit escape of upward exhaust flow from the head. 135
12. A ventilator head having a tubular neck portion; a comparatively deep superimposed co-axial band of larger diameter vertically lapping the upper edge of the neck portion by a slight margin with provision thereabout of a circumferential space constituting a bottom exhaust outlet; and a rain deflecting baffle cap axially within the top of the band having protected radially-arranged elongated openings to permit escape of upward exhaust flow from the head. 140
13. A ventilator head having a tubular neck portion; a comparatively deep superimposed co-axial band of larger diameter vertically lapping the upper edge of the neck portion by a slight margin with provision thereabout of a circumferential space constituting a bottom exhaust outlet; and a rain deflecting baffle cap axially within the top of the band having protected radially-arranged elongated openings to permit escape of upward exhaust flow from the head. 145
14. A ventilator head having a tubular neck portion; a comparatively deep superimposed co-axial band of larger diameter vertically lapping the upper edge of the neck portion by a slight margin with provision thereabout of a circumferential space constituting a bottom exhaust outlet; and a rain deflecting baffle cap axially within the top of the band having protected radially-arranged elongated openings to permit escape of upward exhaust flow from the head. 150

nular clearance aforesaid and prevent it from falling into the neck portion.

7. A ventilator head having a tubular neck portion; a comparatively deep superimposed co-axial band of larger diameter verticallylapping the upper edge of the neck portion by a slight margin with provision thereabout of a circumferential space constituting a bottom exhaust outlet; a rain deflecting baffle cap axially within the top of 10 the band, said cap having protected radial openings defining vertical-diffusive escape of part of the upward exhaust flow from the head and being of an area somewhat less than that of the

band with formation of an annular exhaust outlet clearance at the top of the head; an inner band at the top of the first mentioned band co-active with the baffle cap to form a surrounding annular exhaust outlet; and a downwardly flared guard surrounding the neck portion below the lower edge of and supported by drop arms from the band to prevent upwardly deflected outside air currents from entering the head, and also to outwardly divert rain, sleet or snow entering the head at the top through the annular clearance aforesaid.
